UNITED STATES PATENT OFFICE

NATHANIEL LOMBARD, OF WORCESTER, MASSACHUSETTS, ASSIGNOR OF ONE-HALF TO
EDWARD F. COFFIN, OF WORCESTER, MASSACHUSETTS

CARBONATOR

Application filed March 21, 1931. Serial No. 524,264.

The present invention pertains to structural and functional betterments in liquid carbonators, and relates more particularly, but not necessarily exclusively, to that type of appliance which is commonly employed to provide a supply of the carbonated beverage, or so-called "soda-water" dispensed at soda-fountains.

The customary method in using carbonators employed for this purpose has been to force carbon-dioxide gas, under substantial pressure, into a considerable quantity of water, which, as thus charged, is then stored in auxiliary coolers until required for consumption.

Most of the present devices of this character are not only complicated in construction and difficult to maintain in adjustment, but they are also expensive to produce.

This new invention, on the other hand, is extremely simple in its embodiment in practical form, requiring substantially no attention while in service, and can be manufactured and sold at a comparatively low cost, thus rendering its benefits available to a large number of users who could not afford to pay for the more intricate and expensive appliance.

This invention also successfully overcomes a fault common to carbonators of the water-pressure type by providing effective means whereby the volumes of gas and water, respectively, which are admitted to the carbonator automatically, will be maintained at a substantially-constant and predetermined ratio regardless of material variations in the pressure of the water employed.

When an appliance incorporating this invention is used, no stored supply of soda-water is required, and every glass of the respectively, which are admitted to the carbonated, as drawn, thereby producing a beverage of more effervescent quality than has been possible previously.

Separate coolers heretofore have been necessary in connection with soda-fountains for plain water and soda-water, but, by taking advantage of this invention, only ordinary, plain water will be required to be cooled in advance of its use, and all such water will

be potentially available for carbonated soda-water, thereby increasing or doubling the present capacity of the apparatus.

While, in the past, the uniform idea governing carbonating methods used in the dispensing of soda-water at soda-fountains has been to secure practically-complete saturation of the water with the gas, resulting in the formation of carbonic acid, mixing-chambers of various forms having been employed to accomplish this result, it has now been discovered that, when the carbonating practice applies to soda-water to be dispensed by the glass, such complete gas-saturation is not only unnecessary, but is, in fact, undesirable.

The highly satisfactory results accruing from using the present invention demonstrate that a more sparkling, lively and bubbling beverage results from merely impregnating the water with a suitable amount of quickly evolved gas, retaining these elements in a mechanical relationship, rather than permitting them to combine chemically to form carbonic acid, and, for this reason, appliances incorporating the new invention do not employ a mixing-chamber.

Although the new carbonator is especially suited to meet the requirements for use in soda-fountains or other carbonated-beverage dispensing devices or systems, it can be satisfactorily employed for bottlers' use, and, when thus used, the gas-impregnated water discharged from the carbonator would require introduction into a separate container or storage receptacle where complete saturation could be effected and the mixture "quieted" before passing into the bottle-filling machine.

The especial value of the new device for bottlers' use is due to the opportunity it affords of proportioning accurately the ratio of gas and water at all times, thereby effecting large economies in gas consumption.

To enable those skilled in this art to understand the invention fully, a present, preferred embodiment of the same has been illustrated in detail in the accompanying drawings, to which reference should be had in connection with the following description, like refer-

ence numerals, for simplicity, designating the same parts in the two figures.

In these drawings,—

Fig. 1 is a perspective view of such preferred form of the appliance; and

Fig. 2 is an upright cross-section through the vertical, middle plane of the carbonator, this view representing the several parts of the device in their respective positions when the carbonator is not in operation.

Referring to these drawings, it will be perceived that the improved and novel appliance includes a hollow or tubular casting 11 having at one end a water-inlet 12 leading inwardly directly to a water-chamber 13, the exterior of such end of the member 11 being screw-threaded at 10 for the attachment of the required water-supply pipe or conduit (not shown).

20 In ordinary practice, such end of the apparatus is connected to the city water-main with its water under substantial, but somewhat varying, pressure.

Chamber 13 communicates directly with 25 an aligned, enlarged, cylindrical cavity 14, with a circular shoulder 15 at their junction, such chamber 14 accommodating a coiled spring 16 bearing at its inner end against the shoulder, and pressing at its other extremity 30 against a round, disc-like center-piece or button 17 having a projection or boss 18 fitting inside of the adjacent end of the spring to maintain the parts in proper assembled relation:

35 On the opposite face of the element 17 another central boss or projection 19 extends through registering holes in a flexible diaphragm 21 and a metal washer 22 bearing against the outer surface of the diaphragm 40 and secured to the part 17 by a number of rivets 23, which, of course, occupy suitable holes in the diaphragm provided for their accommodation.

The left-hand end of casting 11 has a substantial, circular enlargement 24 recessed to provide a cylindrical compartment 25 which is of materially greater diameter than the part 17 which it accommodates and which is in direct communication with chambers 14 50 and 13.

Around its periphery, member 24 has a circular flange 26 defining a larger, round cavity 27 which receives the diaphragm, the marginal or border portion of which is securely 55 and firmly clamped between the inner, circular wall of such cavity and the inner face of a gas-valve member 28 fitting inside of the flange 26 and fastened to the element 24 by a number of screws 29, 29 extending through 60 holes in the intervening diaphragm, the latter being of leather, rubber, metal, or of any other appropriate or suitable material.

Thus the three parts 24, 21 and 28 are securely, yet detachably, clamped or held together in fluid-tight relation.

Member 28, on its inner face, has a round gas chamber or recess 31 opposite and matching the water-chamber 25 on the other side of the diaphragm, and it also has an outwardly-projecting hollow or tubular, externally 70 screw-threaded stem 32, the cylindrical chamber 33 which may be in communication with the gas-chamber 31 through a conical gas-port defined by a correspondingly-shaped valve-seat 34, which is directly opposite the center of the boss 19.

A hollow or tubular gas-valve 35 is slideable lengthwise in such cylinder 33, and it has a tapered or conical-shaped nose 36, constituting the valve proper, coacting with the 80 valve-seat 34 and adapted to open and close the gas-port.

As is clearly shown in Fig. 2, the valve-nose 36 extends a short distance into chamber 31 in the closed position of such valve.

The cavity in valve 35 has a larger, longer section 37 open at its outer end and communicating at its inner end directly with a shorter, smaller section 38 which connects with the inner ends of a plurality of apertures 39 leading to the outer face of the otherwise-closed, tapered nose or cone section of the valve outwardly beyond the valve-seat, all as is clearly shown in Fig. 2.

A coiled spring 41 occupies the cavity 37 and presses at one end against the shoulder at the junction of the two cavities 37 and 38 of different calibers, and, at its other extremity, against a centrally perforated or apertured plug 42 screwed into the end of the part 32, 100 the latter being threaded on its outside, as explained, for the coupling thereto of a pipe or conduit leading from a compressed-gas supply-tank through a pressure-regulating valve, both of which are of the well-known and usual construction, and neither of which has been illustrated.

Thus gas at a substantially unchanging pressure, by reason of the operation of the regulator, is admitted into and is present inside of the valve 35.

Casting 11, intermediate its ends, has a hollow, downward extension 43 affording within it a gas space 44 closed at its bottom by a screw-threaded plug 45 and equipped at its 115 top with a gas-nozzle 46 screwed into a threaded hole in the wall of the casting and extending well up into or through the water-chamber 13.

Such nozzle opens at its lower end into the space 44, and its upper end has a small, conical gas-discharge port 47.

Chamber 44, and therefore the inside of the nozzle, is at all times in communication with gas-chamber 31 by means of a passage 48 through the members 43 and 24 and an intervening, hollow connection 49, an aperture 51 through the marginal portion of the diaphragm, and a passage 52 in the clamping member 28.

From the foregoing, it will be clear that the gas-spaces 44 and 31 and the conduit connection between them constitute in effect a single gas-chamber.

5 Directly opposite the downward extension 43, casting 11 has a corresponding or complementary, hollow or tubular, upper extension 53 having a relatively-long and comparatively-large passage or port 54 through its lower part, opening into the water-chamber 13 around the gas-nozzle 46.

Such port is substantially larger in cross-section than, and is in direct alignment with, the gas-nozzle 46, and the latter may extend 15 up into such port a short distance, if desired; Fig. 2 of the drawings showing a present, preferred arrangement of these parts.

Port 54 at its upper end opens into a larger, cylindrical valve-chamber 55, which, in turn, 20 at its top connects with a still-larger, cylindrical, dashpot chamber 56, the upper end of which is internally screw-threaded at 57.

25 A hollow, cylindrical valve-member 58 fits and slides in the cylinder 55, its lower end being formed as a relatively-long cone-valve 59 arranged and adapted to co-operate with and to open and close simultaneously the gas-port 47 of the gas-nozzle 46 and the upper end of the water-port 54.

30 Such double-valve member 58 has a round cavity 61 therein, open at its top end and connecting at its bottom end with a smaller chamber 62 joined by a plurality of radial holes 63 to the outer face of the cone-valve 59 above the top end of port 54.

Such valve is pressed down to its two valve-seats around its pair of ports by a coiled spring 64 occupying the recess 61 and acting at its lower end on the bottom wall of such cavity, and pressing at its top end against a shoulder 65 in a centrally-apertured plug or connector 66 screwed into the upper end of part 53, the terminal portion of such screw plug being screw-threaded on its outside for connection to a pipe or conduit leading to a faucet-equipped soda-fountain draft-arm (not shown).

50 Valve 58 at its top has an outstanding, circular flange 157 fitting the space 56, and the two constitute in effect a dashpot structure steadyng the action of the double valve and preventing it from chattering.

The operation of the improved carbonator occurs substantially as follows:

55 Assuming that the water-inlet 12 has been connected with a source of plain water, under pressure, usually the city service main, and that the gas-inlet 32 has been joined to a drum of compressed carbon-dioxide gas

60 through a pressure-regulating valve, by means of which a pressure of several pounds more than ordinary water-pressure will be maintained in the valve 35, and that the part 66 has been connected to the usual soda-foun-

the latter is closed, the several parts of the appliance will occupy the positions and relations depicted in Fig. 2, the spring 64 being of sufficient strength to hold the cone-valve 59 down to close the two ports 54 and 47 against 70 the action of the water and gas pressures acting thereon tending to open the valve.

Were no such spring employed, the pressures on the two sides of the valve would be practically balanced and there would be no 75 assurance that the two ports were closed.

It will be observed that the water-pressure of the main is always applied to one side of the diaphragm 21 in the chamber 25 and that this pressure is supplemented or augmented 80 by that of the spring 16, and that the gas-pressure in chamber 31 is acting on the opposite side of the diaphragm, these opposing pressures being balanced, so that the diaphragm occupies the central or neutral position illustrated.

Under these circumstances, valve 36 is closed, thus breaking the connection between the supply of gas and the united chambers 31 and 44.

When the valve or faucet of the soda-water draft-arm is opened, the carbonated water already contained within the valve-chamber 55 flows out speedily, thereby producing an immediate pressure reduction in the valve. 95

The city water in port 54, being now at a higher pressure, overcomes the slight action on the valve exerted by the spring 64 and lifts the valve-member 58 and its cone-valve 59 upwardly off of the valve-seat at the upper 100 end of port 54 and simultaneously opens the gas-port 47 of the gas-nozzle 46.

When the valve is raised in this manner, the carbon-dioxide gas which has been confined within the gas-nozzle 46 and chambers 105 44 and 31 escapes at once upwardly along the flaring surface of the conical valve 59, and, mixed with the water of the port or chamber 54 which it impregnates, flows along with the water through the narrow, annular opening 110 between the port 54 and the valve 59, and the water thus carbonated then passes through the perforations 63 of the cone-valve 59, and flowing through the central passage 61, is discharged through the outlet member 66 into 115 the pipe which connects with the draft-arm, through which it is dispensed into the glass.

As soon as the draft-arm is thus set in operation, inducing the flow of carbonated water within the carbonator, a reciprocal 120 movement is instituted in connection with the gas-valve 36 which controls the supply of carbon-dioxide gas admitted into the carbonator.

When the carbonator is not in operation, 125 valve 36 is always closed, being firmly held against its valve-seat 34 due to the gas-pressure, exerted direct from the gas-regulator through the hole of plug 42 and into chamber 33, where it acts directly on the sliding valve- 130

member 35, this pressing action of the gas being supplemented by that of spring 41.

When, however, the faucet or valve in the draft-arm is opened, resulting in the substantially-simultaneous unseating of valve 59 on the gas-nozzle, with the resulting opening of its port 47, the gas previously confined within the diaphragm-chamber 31 escapes through the connected passages 52, 51, 48, 44, and the passage through the gas-nozzle 46, thereby producing a lowering of the pressure on the side of the diaphragm adjacent to the gas-valve 36.

Following this reduction in gas-pressure, the higher water-pressure on the other side of the diaphragm, combined with the action of spring 16, flexes the diaphragm to the left, as the parts are viewed in Fig. 2, carrying the metal button 17 in the same direction until its projection 19 pushes against the end of gas-valve 36, forcing it away from its seat 34 and thus opening the gas-valve.

By reason of such valve opening, the carbon-dioxide gas in chambers 37 and 38 of the sliding-valve-member flows through the perforations 39 and the gas-port into the chamber 31 and its associated connection 52, 51, 48, 44 and 46, bringing about the escape of the gas through the nozzle-port 47, with the resulting continued carbonation of the water, as has already been described.

So long as the valve or faucet in the draft-arm remains open, the volumes of water and gas will continue to flow in exactly proportioned amounts, as controlled by the operation of valve 59, and when the faucet in the draft-arm is closed, the operation of the carbonator terminates instantly, the valve 59 immediately automatically seating itself and closing the two ports 54 and 47, due to the action of spring 64.

This, of course, automatically shuts off all further intake of water and gas and restores the pressures on the two sides of the diaphragm to the equilibrium which regularly exists when the carbonator is not operated.

Valve 36 closes on its valve-seat and the carbonator returns to the conditions which prevailed previously to being set into operation by the opening of the valve in the draft-arm.

In order to obtain the advantageous results specified in the improved type of carbonator, the construction omits any component element of structure designed or adapted to perform the usual function of a mixing-chamber, and this constitutes one of the unique features of the invention and differentiates it from other types of carbonators heretofore used.

Due to the almost simultaneous discharge of the carbonated water from the draft-arm, directly and immediately after the plain water has received its proportioned volume of gas, a less permanent combination of the car-

bon-dioxide gas with the water is effected than is the case when a mixing chamber is employed.

For a satisfactory glass of "soda-water", the principal aim is to obtain as sparkling and effervescent an aerated beverage as can be produced, and in the new appliance incorporating this invention such desirable result is achieved by keeping the respective volumes of water and gas in an impermanent or unstable combination, whereby to bring about a speedier release or discharge of the gas from the water when dispensed from the draft-arm of the soda apparatus.

The carbonated water dispensed or delivered by means of this appliance exhibits a higher degree of effervescence at the moment of dispensing than is possible when the discharged water has absorbed the carbon-dioxide gas into a more permanent or lasting combination through the employment of a mixing-chamber.

Another outstanding feature of this invention is that the amount of gas fed to the water is automatically controlled by the pressure of the latter, and, since the speed of water delivery or flow is substantially proportional to its pressure, then a definite, unchangeable and predetermined ratio of gas to water results, regardless of how much the water-pressure may vary, it being remembered that city service water-pressures are subject to substantial modifications under ordinary conditions.

Inasmuch as the sizes of the two ports 47 and 54 are fixed with relation to one another, and since the same valve controls the opening and closing of both, the ratio of water and gas would remain constant provided their pressures did not vary.

It is desirable to have the gas at a higher pressure than that of the water, and this difference is determined by the strength of spring 16, whose action on the diaphragm supplements that of the water-pressure thereon, or, in other words, the action of the spring opposes the pressure of the gas on the diaphragm.

If, for example, the water-pressure in the service main, and consequently in chambers 13 and 25, decreased, then, during the operation of the carbonator, the gas-valve will be opened a less degree, maintaining a correspondingly-reduced pressure in chambers 31 and 44, so that a less quantity of gas will be fed to the diminished quantity of delivered water, such lessened amount of water discharged from the appliance being due to its reduced pressure therein.

Conversely, if the water-pressure is increased, a greater quantity of water will flow through the apparatus, and gas at a higher pressure and in a correspondingly-increased amount will be fed into the water.

Stated somewhat otherwise, since the amount of flow of water through the appara-

tus depends upon the water-pressure and since the amount of flow of gas depends upon the gas-pressure at the nozzle, and due to the fact that such gas-pressure is controlled directly by the water-pressure, the desired ratio of gas to water can be kept substantially unvarying even though the water-pressure undergoes material changes.

Those acquainted with the art will readily understand that the invention as defined by the appended claims is not limited or restricted to the precise and exact details of construction shown and described, and that more or less radical modifications may be incorporated in the apparatus without departure from the heart, essence or principles of the invention, and without the loss or sacrifice of any of its material benefits or advantages.

20 I claim:

1. In a carbonator, the combination of a hollow body having means to admit liquid under pressure thereinto, having means to admit gas under pressure into said body and into the liquid therein, and having means adapted to deliver the gas-charged liquid therefrom into a faucet-equipped dispensing-apparatus, a first valve controlling the flow of liquid through the carbonator, a second valve controlling the flow of gas into the liquid, means to open and close said valves substantially-simultaneously with the corresponding operation of said faucet, a third valve governing the flow of gas into the carbonator, and means subjected to the opposed action of the liquid and gas pressures in the carbonator controlling the action of said third valve to maintain a substantially-constant volume-ratio of gas to liquid in the gas-charged liquid delivered from the carbonator.

2. In a carbonator, the combination of a hollow body having means to admit liquid under pressure thereinto, having means to admit gas under pressure into said body and into the liquid therein, and having means adapted to deliver the gas-charged liquid therefrom into a faucet-equipped dispensing-apparatus, a first valve controlling the flow of liquid through the carbonator, a second valve controlling the flow of gas into the liquid in the carbonator, means to open and close said valves substantially-simultaneously with the corresponding operation of said faucet, a third valve governing the flow of gas into the carbonator, and automatic means controlling the action of said third valve to maintain a substantially-constant volume-ratio of gas to liquid in the gas-charged liquid delivered from the carbonator including a diaphragm subjected on one side to the liquid pressure in the carbonator and on its other side to the gas pressure in the carbonator and subjected to the gas pressure in the carbonator.

3. In a carbonator, the combination of a

hollow body having means to admit liquid under pressure thereinto, having means to admit gas under pressure into said body and into the liquid therein, and having means adapted to deliver the gas-charged liquid therefrom into a faucet-equipped dispensing-apparatus, a first valve controlling the flow of liquid through the carbonator, a second valve controlling the flow of gas into the liquid in the carbonator, means to open and close said valves substantially-simultaneously with the corresponding operation of said faucet, a third valve governing the flow of gas into the carbonator, and automatic means controlling the action of said third valve to maintain a substantially-constant volume-ratio of gas to liquid in the gas-charged liquid delivered from the carbonator including a diaphragm subjected on one side to the liquid pressure in the carbonator and on its opposite side to the gas pressure in the carbonator, and a spring acting on said diaphragm augmenting the pressure imposed thereon by the liquid.

4. In a carbonator, the combination of a hollow body having means to admit liquid under pressure thereinto, having means to admit gas under pressure into said body and into the liquid therein, and having means adapted to deliver the gas-charged liquid therefrom into a faucet-equipped dispensing-apparatus, a spring-closed valve-means controlling simultaneously the flow of liquid through the carbonator and the flow of gas into the liquid, said valve-means opening and closing automatically simultaneously with the opening and closing of said faucet by reason of changes in the liquid pressure on its delivery side, a diaphragm subjected on one side to the pressure of the liquid in the carbonator, a spring augmenting such liquid pressure on the diaphragm, means subjecting the opposite side of said diaphragm to the pressure of the gas in the carbonator, a gas-inlet valve controlling the admission of gas into the carbonator pressed toward its seat by the gas pressure behind it, and a spring supplementing said gas-pressure action on said gas-inlet valve, the flexing of said diaphragm under said liquid and associated spring pressures opening said gas-inlet valve, whereby to maintain substantially-constant a predetermined volume-ratio of the gas and liquid in the charged liquid delivered from the carbonator.

5. In a carbonator, the combination of a hollow body having means to admit liquid under pressure thereinto, having means to admit gas under pressure into said body and into the liquid therein, and having means adapted to deliver the gas-charged liquid therefrom, said carbonator having a conical liquid-valve port through which the liquid passes as it flows through the carbonator and a smaller concentric conical gas-valve port

6

through which the gas flows into the liquid, a conical valve adapted to open and close both of said ports simultaneously, a third valve governing the flow of gas into the carbonator, and automatic means controlling the action of said third valve to maintain a substantially-constant volume-ratio of gas to liquid in the gas-charged liquid delivered from the carbonator.

5
10 In witness whereof I have hereunto set my hand and seal.

NATHANIEL LOMBARD. [L.S.]
